(57) **CLAIM**

The ornamental design for set of handles for a shopping cart, as shown and described.

DESCRIPTION

FIG. 1 is a rear perspective view of a set of handles for a shopping cart showing our new design;
FIG. 2 is a front perspective view thereof;
FIG. 3 is a front elevational view thereof;
FIG. 4 is the rear elevational view thereof;
FIG. 5 is a right side view thereof;
FIG. 6 is a left side view thereof;
FIG. 7 is a top view thereof;
FIG. 8 is a bottom view thereof;
FIG. 9 is a close-up view of the encircled region of FIG. 1; and,
FIG. 10 is a close-up view of the encircled region of FIG. 2. The left and right handles are being shown alone in FIGS. 9 and 10 for convenience of illustration.
